UNITED STATES PATENT OFFICE.

LINDEN A. THATCHER, OF BELLEVILLE, NEW JERSEY, ASSIGNOR TO UNDERWOOD TYPEWRITER COMPANY, OF NEW YORK, N. Y., A CORPORATION OF DELAWARE.

STENCILING MACHINE.

Application filed June 30, 1923. Serial No. 648,650.

To all whom it may concern:

Be it known that I, LINDEN A. THATCHER, a citizen of the United States, residing in Belleville, in the county of Essex and State 5 of New Jersey, have invented certain new and useful Improvements in Stenciling Machines, of which the following is a specification.

This invention relates to stenciling machines, and is herein illustrated as applied to a machine of the Underwood revoluble duplicator type.

In machines of the type referred to, the usual pressure-roll is raised into position to engage the stencil-cylinder by means of a rock-shaft and an operating arm thereon held in operated position by means of a latch. Upon release of the latch, the pressure-roll is permitted to drop. To vary the pressure to enable the machine to handle sheets of different thicknesses, or to produce light or heavy impressions, and for other purposes, the arm is adjustable about the rock-shaft usually by means of a screw fixed 25 against longitudinal movement in a block pivoted on the operating arm, and threaded into a nut pivotally mounted on another arm fixed on the shaft.

The operator has to turn the screw experimentally in each direction when desiring to increase or decrease the pressure, and, if the screw happens to stand in a position where it is nearly withdrawn from the nut, a slight turn of the screw may cause disconnection of the parts; and in some cases such disconnection may be caused by the jar of the machine.

Inasmuch as a number of turns of the screw may be necessary in changing the adjustment, it is difficult to determine upon the degree of pressure that is to be exerted by the pressure-roll when in effective position.

In the usual machine of such type, the supporting frame for the pressure-roll is flexible, and is lifted by means of a cam on the rock-shaft, referred to, engaging at the middle a cross-rod joining the free ends of the pivoted arms, in which the journals of the pressure-roll are mounted, to produce substantially uniform pressure along the length of the pressure-roll. Due to the flexibility of the frame, the pressure-roll may

move longitudinally, thereby causing shifting of, or injury to, the stencil, and even resulting in the catching of the frame on other parts of the machine, and consequent failure to lower the pressure-roll when the controlling handle is released.

Further disadvantages arise from supporting the journals of the pressure-roll in depressions in the pivoted arms of the supporting frame. The journals may shift longitudinally in the depressions, and, when the parts become corroded or are not kept clean and lubricated, the turning of the stencil-cylinder may cause the journals to ride out of the depressions, thereby causing injury to the stencil and putting the machine out of order.

Also, in such machines, the usual check or brake comprises a substantially horizontal arm to engage the inner surface of the stencil-cylinder when the pressure-roll is released. This arm tends to interfere with the insertion and removal of the stencil-cylinder.

An object of this invention is to provide simple and effective means for overcoming such objections, and for effecting other improvements.

According to the present invention, the adjustment for varying the pressure may be effected by means of a rotatable head, preferably limited in movement to a single complete rotation in either direction, and means is provided to indicate the adjustment for any particular pressure, so that when the pressure of any class of work is known, the adjusting head can be turned at once to the corresponding position. Preferably the indicating means is placed on one face of the adjusting head. For regulating the position of the operating arm around the rock-shaft, the adjusting head may be provided on its inner side with a snail groove, extending substantially once around the axis of the head, and receiving a follower that extends from a lever that is pivoted on the operating arm, and having a tooth engaging between two teeth of a member on the shaft. Inasmuch as the snail groove is limited substantially to one turn, the movement of the adjusting head is likewise limited, preventing disconnection, and the head in its movement from one limiting position to the other eff-

fects all different adjustments of the operating arm around the shaft. Provision may also be made of friction means to hold the adjusting head in each position to which it may be set. It will be evident that disconnection of parts will not be effected by accidental movement of the adjusting head, and that, by the arrangement of numbers with different graduations of the indicating means, the direction of turning for increasing or diminishing the pressure will be evident. Furthermore, an inexperienced operator may set the adjusting head according to directions, whereas, in the usual machine, such setting would depend upon the skill of the operator in effecting the proper adjustment by trial, and it will be seen that after once setting the adjusting head to a given pressure the operating arm may be moved to either of its positions without in any way affecting the adjustment of the pressure-roll.

In order to avoid release of the operating handle without downward movement of the pressure-roll, the lifting and lowering of the supporting frame of the pressure-roll, provision may be made of suitable means, such as a toggle, to connect the rock-shaft with the frame, thereby insuring positive downward movement of the supporting frame as well as positive upward movement. Similar connections with suitable lost motion may be provided to cause the brake to be thrown on as soon as the pressure is withdrawn, and to be thrown off when the pressure-roll is restored to its effective position.

To avoid the disadvantage arising from the ordinary means for mounting the pressure-roll on the supporting frame, provision is made of suitable ball-bearings on the journals of the pressure-roll and held against movement longitudinally thereof, and of spring-clips on the inner faces of the arms of the supporting frame to receive and detain said ball-bearings. It will be seen that by this arrangement the trouble due to insufficient cleaning or lubricating is avoided, and there is substantially no danger of dismounting the pressure-roll in the ordinary operation of the machine.

Due to the use of ball-bearings mounted in the clips or sockets on the pivoted arms of the supporting frame, longitudinal movement of the pressure-roll with reference to the frame will be avoided. To avoid excessive lateral movement of the supporting frame, provision may be made of suitable means, such as a slotted or U-shaped guide receiving one of the pivoted arms.

The cylinder is provided at one end with a hub having a tapered end and a groove back of said tapered end, so that, when a journal projecting from the hub is moved into a suitable bearing on one of the end

frames, a latch pivoted on the bearing will ride up on the tapered end and drop into the groove to hold the stencil-cylinder against longitudinal movement. The brake is also upturned at its inner end so that, during the insertion of the journal into the bearing on the end frame, the edge of the stencil-cylinder will readily pass under the raised end of the brake and cam it into position to engage the inner surface of the end of the stencil-cylinder.

Other features and advantages will hereinafter appear.

In the accompanying drawings,

Figure 1 is an end elevation of a stencil-ing machine with the novel pressure-adjusting means applied thereto.

Figure 2 is a view, taken in section longitudinally of the cylinder, showing the improved means for controlling the pressure-roll and the brake for the cylinder.

Figure 3 is an end elevation, showing the pressure-regulating head set at "0", part of the head being broken away to show the underlying structure.

Figure 4 is a view similar to Figure 3, but showing the pressure-regulating head set at "9".

Figure 5 is a sectional view of the pressure-regulating means taken in a plane containing the axis of the pressure-controlling shaft.

Figure 6 is a fragmentary view, showing the means for supporting one end of the pressure-roll, parts being broken away to show the underlying structure.

Figure 7 is a perspective view, showing one end of the pressure-roll with a ball-bearing thereon.

Figure 8 is a fragmentary perspective view, showing the means for controlling the position of the pressure-roll and the brake for the cylinder.

Figure 9 is a view showing the pressure-roll in position to co-operate with the cylinder, and the brake for the cylinder in ineffective position.

Figure 10 is a view similar to Figure 9, but showing the pressure-roll drawn down from the cylinder and the brake in effective position.

Figure 11 is a view similar to Figure 10, the pressure-roll and the controlling means therefor being omitted to show the brake and the controlling means therefor.

A stencil-cylinder 15 is mounted in end frames or standards 16 and 17, respectively, of a frame 18. At the end, supported in the standard 16, the stencil-cylinder is provided with an annular head 19 mounted on trundles 20, 21 and 22 rotatably mounted on the standard 16. At its other end, the stencil-cylinder 15 is provided with a head 23 comprising a hollow hub 24 and spokes 25 radiating therefrom to an annular flange 26.

A stub-shaft 27 fixed within the upper portion 28 of the standard 17 provides a bearing upon which the hub 24 revolves. Pivoted on a pin 29 on the standard 17 is a latch 30 controllable by a finger-piece 31 and having a downwardly-extending end 32 to ride up on the tapered end of the hub of the head 23 to drop into a groove 33 on the hub and thereby hold the cylinder against longitudinal movement.

Beneath the cylinder 15 is a pressure-roll 34 rotatably supported in arms 35 pivoted by means of shouldered screws 36 in bosses 37 projecting inwardly from the end frames. The arms 35 are raised to bring the pressure-roll 34 into effective position, and also are drawn downwardly therefrom by means of a finger-piece 38 on an arm 39 mounted on a rock-shaft 40 having fixed thereon an arm 41 forming part of a toggle which also comprises a link 42 pivoted to the outer end of the arm 41 and rotatably mounted at the other end on a cross-member or rod 43 joining arms 35, as shown in Figure 2. The upper end of the link 42 is limited in movement along rod 43 by means of collars 44 held against outward movement by means of split pins 45 passed through perforations in the rod 43. To hold the arm 39 in operative position, provision is made of a latch 46 having a hook 47 to receive the reduced end 48 of the arm 39, and releasable by a finger-piece 49 on the latch 46.

To hold the stencil-cylinder 15 against accidental rotation, when the pressure-roll 34 is withdrawn therefrom, as when positioning a stencil upon said stencil-cylinder, provision is made of a brake 50 provided with a lining 51 to engage a portion 52 of the annular flange forming part of the head 23. The brake 50 is substantially U-shaped to extend around the edge of the annular flange 26, and the lower branch of the U-shaped portion is carried on the end of a lever or arm 53 pivoted on one of the shouldered screws 36, and the arm 53 is urged downwardly by a spring 54 to bring the brake into engagement with the annular flange 26. To place the brake 50 under the control of the finger-piece 38, an arm 55 is secured to the shaft 40 and is pivoted at its outer end to the lower end of a link 56 by means of a shouldered screw 57. At its upper end the link 56 is provided with a slot 58 to receive a pin 59 projecting from the arm 53. Upon depressing the finger-piece 38, the pressure-roll 34 will be lifted to effective position. At the beginning of the upward movement of the pressure-roll 34 no effect will be produced on the brake 50, but, as the link 56 reaches a position to bring the lower end thereof into engagement with the pin 59, the arm 53 will be actuated against the action of the spring 54 to release the stencil-cylinder. Obviously, as soon as

the pressure-roll starts to move down, the brake 50 becomes effective on the stencil-cylinder 15.

In the usual form of machine, no provision is made for releasing the brake 50 except in connection with the raising of the pressure-roll, but in applicant's construction an opening 60 is provided in the standard 17 to permit a finger-piece 61 to pass therethrough to become accessible at the side of the machine. By lifting the finger-piece 61 the brake 50 may be released against the action of the spring 54. It should be noted that the inwardly-projecting arm 62 of the brake 50 is inclined upwardly so as to facilitate the insertion of the reduced portion 52 of the annular flange 26 beneath the end of the brake when the latter is in effective position. This structure of the brake in connection with the beveled end of the hub at the right-hand end of the cylinder, as shown in Figure 2, facilitates the insertion and removal of the stencil-cylinder.

When in use, work-sheets, not shown, are inserted, one by one, over a table 63 and beneath a deflector 64 into position to be gripped between the stencil-cylinder 15 and the pressure-roll 34. At each side the deflector 64 is provided with a stripping finger 65 projecting toward the delivery side of the machine.

In stenciling machines, heretofore in use, difficulty has arisen from the tendency of the pressure-roll to work endwise relatively to the stencil-cylinder and displace or injure the stencil. As herein disclosed, the arms 35 and the rod 43 form a frame which tends to hold the pressure-roll more firmly than in machines formerly in use, but to guard against excessive lateral movement of the arms 35, provision is made of a bracket 66 having an upwardly-extending U-shaped portion 67 having a slot 68 to receive one of the arms 35.

Furthermore, in the machines heretofore in use, the journals of the pressure-rolls are usually held in shallow depressions in supporting arms, and, when dirt accumulates around the journals and in the depressions, the rotation of the cylinder may cause the journals to ride out of the depressions, thus tending to tear the stencil-sheet, and temporarily put the machine out of commission. As herein disclosed, ball-bearings 69 are mounted on journals 70 at the end of the shaft 71 on which the pressure-roll 34 is mounted, and each of the ball-bearings 69 is releasably held in a socket 72 secured to the corresponding arm 35 by means of screws 73. It should be understood that the sockets 72 are of resilient material and that when the ball-bearings 69 are pressed against the flared ends 74 of the sockets 72 the flared ends will be forced outwardly, and, as the ball-bearings 69 are inserted, will clip the

same to retain them in the sockets. It will be seen that by this arrangement friction is reduced, and the tendency to displace the pressure-roll is eliminated. As shown in 5 Figure 6, each of the ball-bearings 69 includes a set of balls 75 running in a circular depression or track 76 in an end of the corresponding journal 70, and held in position by a shell 77 having an inner flange 78 engaging the balls 75 on one side and a narrow flange 79 to retain an annular plate 80 in contact with the balls 75 on the outer side of the ball-bearing.

To vary the pressure of the roll 34 on the 15 cylinder 15 to cause light and heavy impressions on the work-sheets, and for other purposes, provision is made of means to adjust the position of the arm 39 around the shaft 40. To this end, the arm 39 is mounted 20 loosely on the shaft 40, which is flattened at 81, and a gear or member 82 having a correspondingly shaped opening is fitted upon the flattened end of the shaft and is thereby held against rotation thereon. The member 25 or gear 82 may be provided with two teeth 83 to receive therebetween a tooth 84 on a bell-crank or lever 85 pivoted on the arm 39 by suitable means, such as a shouldered screw 86, and having an arm 87 with a lateral projection 88 extending into a spiral groove 89 at the inner side of a rotatable adjusting head 90, pivotally mounted on the outer end of the shaft 40 by means of a screw 91 pressing a resilient friction washer 35 92 against the outer face of the head. For convenience in effecting similar settings of the head 90 at different times, the head is provided on its outer face with graduations 93 running from "0" to "9", and with 40 shorter graduations 94 midway between the successive graduations 93, the position of the head being determined by the graduations 93 and 94 in connection with an index or mark 95 on the arm 39.

45 The rotation of the stencil-cylinder 15 may be effected by means of a handle 96 secured to the annular head 19 by suitable means, such as a screw 97. Provision may also be made of a pin or projection 98, on an arm 50 99 adjacent the handle 96, to engage at the end of each rotation a pin 100 which, in the usual manner, thrusts outwardly a pin or stop 101 into the path of pin 98 to check the stencil-cylinder 15 preparatory to inserting 55 another work-sheet.

Variations may be resorted to within the scope of the invention, and portions of the improvements may be used without others.

Having thus described my invention, I 60 claim:

1. In a stenciling machine, a stencil-cylinder, a pressure-roll to co-operate with the bottom thereof, means, including a rock-shaft, for pressing said roll against the cylinder, a handle on said rock-shaft for oper-

ating the same, and means to adjust the handle around said shaft comprising a rotatable adjusting head having a limited movement to prevent accidental disengagement. 70

2. In a stenciling machine, a stencil-cylinder, a pressure-roll to co-operate with the bottom thereof, means, including a rock-shaft, for pressing said roll against the cylinder, a handle on said rock-shaft for operating the same, and means to adjust the handle around said shaft comprising a rotatable adjusting head limited to one complete turn, and having a scale thereon to co-operate with an index on said handle to indicate the position of the handle relative to the shaft. 75

3. In a stenciling machine, a stencil-cylinder, a pressure-roll to co-operate with the bottom thereof, means, including a rock-shaft, for pressing said roll against the cylinder, a handle on said rock-shaft for operating the same, and means to adjust the handle around said shaft comprising a rotatable adjusting head having a limited movement 80 to prevent accidental disengagement, and a friction device to hold said head in any adjusted position. 85

4. In a stenciling machine, a stencil-cylinder, a pressure-roll to co-operate with the bottom thereof, means, including a rock-shaft, for pressing said roll against the cylinder, a handle on said rock-shaft for operating the same, and means to adjust the handle around said shaft comprising a rotatable adjusting head having a limited movement 90 to prevent accidental disengagement, and a scale at the periphery of said head to indicate the position of the handle relative to the shaft. 95

5. In a stenciling machine, a revoluble stencil-cylinder, a pressure-roll to co-operate with the bottom thereof, means, including a rock-shaft, for raising and lowering said roll, a handle mounted on said shaft, a catch to hold said handle in effective position, and means to adjust said handle around said shaft to vary the pressure exerted by the roll when moved to effective position, including a toothed member fixed on said shaft outside said handle, a bell-crank pivoted on said handle and having a tooth on one arm to engage between said tooth and a pin projecting from the side of the other arm, and a revoluble head on said shaft having on its inner side a groove to receive said pin and consisting of a single turn of a spiral to effect all adjustments by one complete revolution and to prevent accidental disconnection of the adjusting means. 10

6. In a stenciling machine, a revoluble stencil-cylinder, a pressure-roll to co-operate with the bottom thereof, means, including a rock-shaft, for raising and lowering said roll, a handle mounted on said shaft, a catch to hold said handle in effective position, and 11

means to adjust said handle around said shaft to vary the pressure exerted by the roll when moved to effective position, including a toothed member fixed on said shaft 5 outside said handle, a bell-crank pivoted on said handle and having a tooth on one arm to engage between said tooth and a pin projecting from the side of the other arm, a revolute head on said shaft having on its 10 inner side a groove to receive said pin and consisting of a single turn of a spiral to effect all adjustments by one complete revolution and to prevent accidental disconnection of the adjusting means, and a friction 15 device to hold said head in any adjusted position.

7. In a stenciling machine, a stencil-cylinder, a pressure-roll to co-operate therewith, a frame for supporting said roll and comprising two pivoted arms connected by a cross-member, and a guide-member having a slot to receive one of said arms and prevent excessive lateral movement of said frame.

8. In a stenciling machine, a stencil-cylinder, a pressure-roll to co-operate therewith, 25 journals at the ends of said roll, ball-bearings mounted on each of said journals and held against movement longitudinally thereof, and a frame for supporting said roll and comprising arms having openings to receive said journals, and a spring clip on each of said arms to receive and detain said ball-bearings.

9. In a stenciling machine, a stencil-cylinder, a pressure-roll to co-operate therewith, 35 journals at the ends of said roll, ball-bearings mounted on each of said journals and held against movement longitudinally thereof, and a frame for supporting said roll and comprising arms and a spring clip on each 40 of said arms to receive and detain said ball-bearings.

10. In a stenciling machine, a stencil-cylinder, a pressure-roll to co-operate therewith, 45 a frame for supporting said roll and comprising two pivoted arms connected by a cross-member, and a toggle for shifting the pressure-roll, connected with said cross-member near the middle thereof, to equalize 50 the pressure of the pressure-roll on the cylinder.

11. In a stenciling machine, a stencil-cylinder, a pressure-roll to co-operate therewith, 55 a rock-shaft beneath said roll, an actuating handle for said shaft, and connections between said roll and said shaft for positively moving said roll toward and from said cylinder, said roll being adjustable relatively to said handle to alter the throw 60 thereof and thereby vary the degree of pressure exerted by said roll against the cylinder.

12. In a stenciling machine, a stencil-cylinder, a pressure-roll to co-operate therewith, 65 a rock-shaft beneath said roll, an ac-

tuating handle for said shaft, and toggle connections between said roll and said shaft for positively moving said roll toward and from said cylinder, said roll being adjustable relatively to said handle to alter the 70 throw thereof and thereby vary the degree of pressure exerted by said roll against the cylinder.

13. In a stenciling machine, a stencil-cylinder open at one end and having at the 75 other end a frame comprising an outwardly-extending collar having a peripheral groove and a tapered outer end, a hub extending beyond the beveled end of said collar, means to support the open end at its periphery, a bearing to receive said hub, a latch on said bearing to ride up on the tapered end of the collar and to drop into said groove, and a 80 brake to engage the inner surface of the cylinder at the end adjacent the hub, said brake being flared away from the inner surface of the cylinder at its inner end, both the latch and the brake being cammed to one side as the hub of the cylinder is inserted into its bearing. 90

14. In a stenciling machine, a stencil-cylinder, a pressure-roll, a brake urged to engage the inside of the cylinder adjacent said roll, and means to press the roll against the cylinder and withdraw the brake and vice 95 versa, comprising a rock-shaft, a pressure-roll-controlling toggle operable by the rock-shaft, and a brake-controlling toggle having a lost-motion connection, so as to be ineffective to throw off the brake until the pressure- 100 roll is near its effective position.

15. In a stenciling machine, a frame having a bearing at one end, a removable cylinder having a hub to fit said bearing, means for automatically engaging and holding the 105 hub against longitudinal movement when the hub is inserted in the bearing, and a brake, to engage the inside of the cylinder, in the path of the cylinder as it is inserted in the frame, said brake having an inclined end 110 so as to ride up inside of the cylinder.

16. In a stenciling machine, a frame having a bearing at one end, a removable cylinder having a hub to fit said bearing, automatic means for clamping the hub against 115 longitudinal movement in the bearing when the cylinder is inserted in the frame, and an inside brake for the cylinder arranged to avoid interference with the insertion or withdrawal of the cylinder from the frame 120 when the brake is in effective position.

17. In a stenciling machine, a frame, a 125 revolute cylinder insertible longitudinally in said frame, and an inside brake yieldably urged to hold the cylinder against rotation, and comprising an inclined brake-arm to be cammed into the cylinder when the cylinder is inserted in the frame.

18. In a stenciling machine, a frame, a 130 stencil-cylinder, a pressure-roll, arms, each

- 5 pivoted to the frame at one end and supporting one end of the pressure-roll at the other, a cross-member connecting the arms, and a toggle connected to the middle of the cross-member to permit equalization of the pressure on the stencil-cylinder when the toggle is operated to press the roll against the cylinder.
- 10 19. In a stenciling machine, the combination of a stencil-cylinder, a pressure-roll to co-operate therewith, means to press the pressure-roll against the cylinder, and means, including a cam having a spiral groove, for adjusting the feed-roll pressure.
- 15 20. In a stenciling machine, a stencil-cylinder, a pressure-roll, and means for shifting the roll toward and from the cylinder, comprising a toggle, a rock-shaft for actuating the toggle, an arm for rotating the shaft, a catch for holding the arm in operated position, and means for adjusting the arm around the shaft to vary the pressure of the roll when moved against the cylinder, comprising a gear having two teeth and being fixed on the shaft, a bell-crank on said arm having one branch provided with a tooth fitting between the gear teeth and the other branch provided with a projection, and a head rotatable on said shaft and having a spiral groove to receive said projection so that rotation of said head will shift said bell-crank and cause a relative movement between said arm and said shaft.
- 25 21. In a stenciling machine, a stencil-cylinder, a pressure-roll, and controlling means for said roll, comprising a rock-shaft, a two-toothed gear fixed on the shaft, a lever for rotating the shaft, loosely mounted thereon, a bell-crank pivoted on the lever and having one arm provided with a tooth fitting between the teeth of the gear, and a cam having a spiral groove to receive the second arm of the bell-crank for shifting the bell-crank and thereby varying the relative positions of the bell-crank and the gear.
- 30 22. In a stenciling machine, the combination of a stencil-cylinder, a pressure-roll, means for varying the pressure of the roll on the stencil-cylinder when the machine is set for operation, and means, including a graduated scale, for indicating the setting of said varying means.
- 35 23. In a stenciling machine, a stencil-cylinder, a pressure-roll to co-operate therewith and having journals projecting from its ends, ball-bearings mounted on each of said journals and held against movement longitudinally thereof, arms for supporting the pressure-roll, and spring cups on the arms for receiving and detaining the ball-bearings.
- 40 24. In a stenciling machine, a stencil-cylinder, a pressure-roll, a brake contacting with the cylinder when the pressure-roll is withdrawn therefrom, means for simul- taneously pressing the roll against the cylinder and withdrawing the brake, including a lost-motion connection to the brake, so as to delay casting off of the brake until the roll is nearly in operative position and to throw on the brake at the beginning of the withdrawing movement of the roll.
- 45 25. In a stenciling machine, a stencil-cylinder, a pressure roll therefor, means for adjusting the degree of pressure of said roll against the cylinder, and means for moving the adjusted roll toward or away from the cylinder, said adjusting means operating independently of and being unaffected by said roll-moving means during operation thereof.
- 50 26. In a stenciling machine, a stencil-cylinder, a pressure roll therefor, means for moving said pressure roll toward or away from the cylinder, and means for adjusting the degree of movement of said roll-moving means, whereby to vary the pressure of said roll against the cylinder.
- 55 27. In a stenciling machine, a stencil-cylinder, a pressure roll therefor, means including an actuating arm for moving the roll toward or away from the cylinder, and means for adjusting the length of throw of said arm, whereby to vary the degree of pressure exerted by said roll against the cylinder.
- 60 28. In a stenciling machine, a stencil-cylinder, a pressure roll therefor, means including an actuating arm for moving the roll toward or away from the cylinder, means for adjusting the length of throw of said arm, whereby to vary the degree of pressure exerted by said roll against the cylinder, and releasable means for engaging said actuating arm to hold the roll against the cylinder in adjusted relation.
- 65 29. In a stenciling machine, a stencil-cylinder, a pressure roll therefor, means for moving said pressure roll toward or away from the cylinder, and a camming device movable to adjust the relation of said roll-moving means with respect to the roll, whereby to alter the length of travel of said roll-moving means and thereby vary the degree of pressure exerted by said roll against the cylinder.
- 70 30. In a stenciling machine, a stencil-cylinder, a pressure roll therefor, means for moving said pressure roll toward or away from the cylinder, and a camming device movable to adjust the relation of said roll-moving means with respect to the roll, whereby to alter the length of travel of said roll-moving means and thereby vary the degree of pressure exerted by said roll against the cylinder, said camming device operating through a long range of movement to thereby provide a fine adjustment.
- 75 31. In a stenciling machine, a stencil-cylinder, a pressure roll therefor, means for moving said pressure roll toward or away from the cylinder, and a camming device movable to adjust the relation of said roll-moving means with respect to the roll, whereby to alter the length of travel of said roll-moving means and thereby vary the degree of pressure exerted by said roll against the cylinder, said camming device operating through a long range of movement to thereby provide a fine adjustment.

from the cylinder, and a camming device movable to adjust the relation of said roll-moving means with respect to the roll, whereby to alter the length of travel of said roll-moving means and thereby vary the degree of pressure exerted by said roll against the cylinder, said camming device turnable through a complete revolution, whereby to accomplish a fine adjustment 10 through a long range of movement.

32. In a stenciling machine, a stencil-cylinder, a pressure roll therefor, means for moving said pressure roll toward or away from the cylinder, and a camming device 15 movable to adjust the relation of said roll-moving means with respect to the roll, whereby to vary the degree of pressure exerted by the latter against the cylinder, said camming device operating through a long 20 range of movement to thereby provide a fine adjustment and effecting a locking action with said moving means to hold the latter and the pressure roll in adjusted relation.

33. In a stenciling machine, a stencil-cylinder, a pressure roll therefor, means for supporting said pressure roll, an actuating arm for operating the supporting means whereby to move the roll toward or away from the cylinder, means for adjusting the 25 position of said arm with relation to said supporting means, whereby to adjust the degree of pressure exerted by the roll against the cylinder, and means for holding the arm whereby to retain the roll against the cylinder, said holding means being releasable to 30 permit the roll to move away from the cylinder.

34. In a stenciling machine, a stencil-cylinder, a pressure roll therefor, a carrier for 10 the pressure roll, an actuating arm for causing said carrier to move the pressure roll toward or away from the cylinder, a camming device movable to adjust the position 15 of said carrier relatively to said arm, whereby to adjust the degree of pressure exerted by the roll against the cylinder, and means automatically engaging said arm to retain the roll when moved against the cylinder, said means releasable to permit said 20 roll to move away from the cylinder.

35. In a stenciling machine, a stencil-cylinder, a pressure roll therefor, means for moving said pressure roll toward or away from the cylinder, and an adjustable camming device between said roll-moving means 25 and the pressure roll, whereby to vary the pressure of said roll against the cylinder, said device operating independently of and unaffected by said roll-moving means.

36. In a stenciling machine, a stencil-cylinder, a pressure roll therefor, a swingable frame for supporting said pressure roll, a rock-shaft, an equalizing connection between 30 said rock-shaft and said frame, an arm for actuating said rock-shaft, and a movable con-

nection between said actuating arm and the rock-shaft including a graduated wheel 70 movable through a long range to effect a fine angular adjustment between said arm and the rock-shaft to alter the length of travel of said arm and thereby vary the pressure of said roll against the cylinder.

37. In a stenciling machine, a stencil-cylinder, a pressure roll therefor, an actuating arm for moving said pressure roll toward or away from the cylinder, means for adjusting said actuating arm relatively to the roll whereby to adjust the degree of pressure exerted by the latter against the cylinder, said means including an adjusting wheel 75 having a long spiral slot, and means carried by said arm and engaging said slot, whereby, when the wheel is turned, said spiral slot effects a relative movement of said actuating arm with relation to the pressure roll.

38. In a stenciling machine, a stencil-cylinder, a pressure roll therefor, a support for 80 said pressure roll, means for actuating said support whereby to move said roll toward or away from the stencil-cylinder, and means for preventing accidental rotation of the cylinder when the roll is moved away therefrom, said last-named means being independently operable to release said cylinder.

39. In a stenciling machine, a stencil-cylinder, a pressure roll therefor, a support for 85 said pressure roll, means for actuating said support whereby to move said roll toward or away from the stencil-cylinder, and a brake engaging said cylinder when the pressure roll has moved away therefrom, said brake being independently operable to release the cylinder to permit the same to be 90 removed from the machine, or to facilitate replacement of said cylinder.

40. In a stenciling machine, a stencil-cylinder, a pressure roll therefor, means including a rock-shaft and an actuating arm for pressing said roll against the cylinder or withdrawing the roll therefrom, and means 100 for adjusting the arm angularly about the shaft whereby to vary the pressure of said roll against the cylinder, said means including a calibrated adjusting wheel co-operating with an index on said arm to indicate 105 the degree of pressure of said roll against the stencil-cylinder.

41. In a stenciling machine, a stencil-cylinder, a pressure roll to co-operate therewith, means including a rock-shaft for moving said roll toward or away from the cylinder, a handle on said rock-shaft for operating the same, and means for connecting and adjusting the handle around said shaft whereby to vary the pressure of said roll 110 against the cylinder, said shaft having a locking action with said handle whereby to maintain the latter in any adjusted position.

42. In a stenciling machine, a stencil-cyl-

inder, a pressure roll to co-operate therewith, means including a rock-shaft for moving said roll against or away from the cylinder, a handle on said rock-shaft for operating the same and means for connecting and adjusting the handle around said shaft to alter the length of throw of said handle and thereby vary the pressure of said roll when moved against the cylinder, said adjusting means including an indexing device for indicating the setting thereof.

43. In a stenciling machine, a stencil-cylinder, a pressure roll to co-operate therewith, means including a rock-shaft and a handle thereon for moving said roll against or away from the cylinder, means for connecting and adjusting the handle around said shaft whereby to vary the pressure of said roll against the cylinder, said adjusting means including an indexing device for

indicating the setting thereof, and a friction device for preventing accidental movement of said indexing device when adjusted to any position.

44. In a stenciling machine, a stencil-cylinder, a pressure roll to co-operate with the bottom thereof, means including a rock-shaft and a handle on said rock-shaft for moving said roll toward or away from the cylinder, a calibrated adjusting wheel connecting said handle to the shaft, said wheel effective, when turned, to change the relation of the handle with respect to the shaft whereby to alter the length of throw of said handle and thereby vary the pressure of said roll against the cylinder, and means for preventing lateral movement of said roll relative to the cylinder.
